CLAIM

The ornamental design for a cassette filter manifold, as shown and described.

DESCRIPTION

FIG. 1 is a perspective view of a cassette filter manifold according the present invention, depicted along with a filter for context;

FIG. 2 is a front view thereof;

FIG. 3 is a rear view thereof;

FIG. 4 is a left view thereof;

FIG. 5 is a right view thereof;

FIG. 6 is a top view thereof; and

FIG. 7 is a bottom view thereof.

FIG. 8 is a perspective view of a cassette filter manifold according the present invention;

FIG. 9 is a front view thereof;

FIG. 10 is a rear view thereof;

FIG. 11 is a left view thereof;

FIG. 12 is a right view thereof;

FIG. 13 is a top view thereof; and,

FIG. 14 is a bottom view thereof.

Portions that are shown as broken lines are for illustrative purposes only and form no part of the claimed design. Portions not shown in the drawings are not visible during use and form no part of the claimed design.
